UNITED STATES PATENT OFFICE.

FRANK PARDEE, OF HAZLETON, PENNSYLVANIA.

SCRAPER FOR CHAIN CARRIERS.

1,176,849.

Specification of Letters Patent.

Patented Mar. 28, 1916.

Application filed February 6, 1913, Serial No. 746,600. Renewed February 11, 1916. Serial No. 77,791.

To all whom it may concern:

Be it known that I, FRANK PARDEE, a citizen of the United States, residing in the city of Hazleton, county of Luzerne, and 5 State of Pennsylvania, have invented certain new and useful Improvements in Scrapers for Chain Carriers, of which the following is a specification, reference being had to the accompanying drawings, forming 10 a part hereof.

In a general way the invention relates to carriers of various kinds and more particularly to that class of carriers or conveyers which are used at coal mines or coal breakers for getting rid of the slate and impurities taken out of the coal after it comes from the mines, and also for conveying the ashes and other refuse by means of an endless chain working on sprocket wheels and propelled by suitable motive power.

More specifically the invention relates to the scraper which works in a runway of trough like formation with flat bottom and upright sides.

25 The object of the invention is to produce a scraper which can be attached to the chain carrier and held in operative position by a simple device, while permitting attachment and detachment of the scraper without great 30 inconvenience or trouble.

The invention consists in a scraper stamped and formed from a blank of sheet metal, the scraper being combined with a retaining clevis, and in the features of construction to 35 be hereinafter more fully described and pointed out or indicated in and by the claim.

In the drawings Figure 1, is a perspective view of the scraper, retaining clevis, and a 40 portion of the carrier chain. Fig. 2, is a side elevation, partly in section, of the trough or runway showing several scrapers and refuse materials to be conveyed to the dump heap. Fig. 3, is a front elevation of the 45 scraper and its retaining clevis and shows in section, the link to which the scraper is attached. Fig. 4, is an edge view of the scraper showing one end of the retaining clevis, the full link to which the scraper is attached and a broken part of the connecting 50 adjacent links of the chain carrier.

In the drawings A, represents the scraper B, the clevis and C, the chain. In Fig. 2, the trough D, is also shown.

The scraper A, is formed from a blank 55 cut of sheet metal, of a pattern that will

give the scraping part a length adapted to the width of the trough across which it extends. The upper part of the blank is somewhat narrower than the lower part, being inset from the corners a , a , upward. This 60 upper part is also cut out in the center so as to straddle a link of the chain C, and on each side of the chain the metal is turned over and forms knuckles a' , a' , for admitting the long arm b, of the clevis B, which 65 is preferably of a length to permit of its being bent and turned down at b' , as seen in Figs. 1, and 3. The short arm b^2 , of the clevis B, passes through a knuckle a^2 , formed by rolling over some of the metal which is 70 cut to admit the chain C.

The scraper A, may be provided with flanges a^3 , a^3 , so that when a vertical link of the chain is admitted in the center space the flanges a^3 , a^3 , bear broadside along a 75 portion of the link which serves to keep the scraper in alinement across the bottom of the trough D. This, however, may be effected by any suitable means integral with either the clevis or the scraper or separate therefrom, but it is desirable to have as few attachments and parts as may be consistent with practical efficiency. The lower knuckle a^2 , through which the clevis passes and the corners a , a , afford bearings for the clevis, 80 at the back of the scraper, to aid in sustaining the load carried in front of it, as seen in Fig. 2, but the scraper may be connected with the chain and reversed so as to come behind the link if desired. When the clevis 85 B, is constructed with one long and one short arm, the long arm is bent over, as shown, and this avoids the necessity for extra securing devices in the way of keys, etc., which may, however, be used if preferred. 90 95

Having thus described my invention, what I claim as new and desire to secure by Letters Patent is:

A scraper for chain carriers, formed of sheet metal having knuckles with space for 100 admitting a link of the chain between them, in combination with a clevis having one long and one short arm, said arms passing through said knuckles, whereby said scraper may be attached to a carrier chain.

FRANK PARDEE.
